UNITED STATES PATENT OFFICE.

SYDNEY I. PRESCOTT, OF BROOKLYN, NEW YORK, ASSIGNOR TO MOTORFLEX EQUIPMENT COMPANY, A CORPORATION OF NEW YORK.

ENGINE-STARTING DEVICE.

1,085,482.

Specification of Letters Patent. Patented Jan. 27, 1914.

Application filed January 20, 1913. Serial No. 743,000.

To all whom it may concern:

Be it known that I, SYDNEY I. PRESCOTT, a citizen of the United States, residing at Brooklyn, county of Kings, and State of New York, have invented a new and useful Improvement in Engine-Starting Devices, of which the following is a specification.

This invention relates to an improvement in engine starting devices particularly designed for use in connection with automobiles.

Heretofore various types of engine starting devices have been used in connection with automobiles and they may be divided into three general classes, namely: electrically operated, gas operated and compressed air devices. The electrically operated starters involve the installation and use of a dynamo, a motor and a storage battery and more or less complicated wiring with which the ordinary automobile driver is totally unacquainted and which cannot be repaired in an ordinary automobile repair shop. Moreover, they are heavy and expensive.

The gas starters heretofore used are provided with means for projecting gas into the cylinders of the engine and there exploding it. The acetylene gas commonly used in such devices is more or less destructive to the cylinders and pistons of the engine. Both the electric battery and the acetylene gas devices require careful attention in order to keep them up to their highest efficiency. The compressed air starters heretofore used have been commonly provided with a small air compressing pump manually thrown into action when it is necessary to store air in the tank provided for the purpose. This also requires attention upon the part of the driver. In these compressed air starters, it is common to pipe the air to a distributing valve from which it is led to the cylinders of the engine and the pressure there used to turn the engine over. This involves a more or less complicated system of piping with many joints which frequently cause trouble through leakage. Moreover, the use of compressed air in the engine cylinders tends to chill the same which interferes with the action of the engine when the gas is first turned on.

The main object of the present invention is the production of an engine starter for automobile and other engines in which a

pre-determined tank pressure is automatically maintained.

A further object of the invention is the production of a device of this general character in which the starting device is automatically thrown out of action when the pressure has fallen to a pre-determined degree.

Still another object is the production of an engine starting device which cannot be operated unless the speed changing mechanism of the driving plant is in a neutral position, thereby preventing the possibility of starting the automobile when the driver has been careless and left his speed changing gears in mesh.

Still another object is the production of a device of the character indicated having a connection whereby the starting mechanism cannot be operated unless the controlling switch of the ignition system is in operative position so that it is impossible for a careless driver to waste his compressed air when the ignition system of the automobile is out of action.

Still another object of the invention is the production of a compressed air starting system in which the air stored in the tank is automatically cut out from the starting motor so that there can be no leak from the tank to the starting motor except when it is necessary to operate the same.

Still another object of the invention is the production of a starting device controlled entirely by one of the controlling elements of the necessary driving mechanism of the automobile, such for instance as the speed changing lever; in other words, a starting device which requires no separate or additional controlling element, but which is controlled by one of the essential elements of the driving mechanism.

Still another object is the production of a device of the character mentioned in which the piping and joints therefor are reduced to a minimum.

Still another object is the production of a device of the character mentioned connected and cooperating with the main driving plant of the automobile and entirely disconnected from the cylinders of the engine.

Still another object is the production of a convertible pressure pump and starting motor, the device being controlled manually

as a motor but controlled automatically when operating as a pump.

Still another object is the production of a device of the general character mentioned which is simple, inexpensive, of light weight, automatically lubricated and operated without any attention upon the part of the driver except when it is necessary to start the engine and then the only thing necessary for the driver to do is to throw the controlling lever into starting position, this being the lever by means of which he shifts his gears so that it is not even necessary for him to shift his hand from one lever to another.

With these and other objects not specifically mentioned in view, the invention consists in certain combinations, constructions, parts and improvements which will be hereinafter fully described and then specifically set forth in the claims hereunto appended.

In the accompanying drawings, which form a part of this specification and in which like characters of reference indicate the same or like parts, Figure 1 is a perspective view of a chassis equipped with mechanism and devices constructed in accordance with the invention. Fig. 2 is a plan view partly broken away of the main part of the starting device inbuilt with the speed changing mechanism. Fig. 3 is a front end view of part of the structure shown in Fig. 2. Fig. 4 is a rear end view of the same. Fig. 5 is a central longitudinal sectional view taken on the line 5—5 in Fig. 2. Fig. 6 is a corresponding sectional view of the upper part of the structure shown in Fig. 5 but showing the rotating valve in the motor operating position. Fig. 7 is a plan view taken on the line 7—7 in Fig. 3. Fig. 8 is a detail sectional view taken on the line 8—8 in Fig. 7. Fig. 9 is a detail sectional view taken on the line 9—9 in Fig. 2. Figs. 10, 11, and 12 are respectively cross-sectional detail views taken on the lines 10—10, 11—11 and 12—12 in Fig. 6, but shown on an enlarged scale. Fig. 13 is a detail plan sectional view taken on the line 13—13 in Fig. 3. Fig. 14 is a sectional plan view taken on the line 14—14 in Fig. 4, but shown on an enlarged scale. Fig. 15 is a sectional view taken on the line 15—15 in Fig. 2, but shown on an enlarged scale. Fig. 16 is a fragmentary detail plan view taken on the line 16 in Fig. 5. Fig. 17 is a detail elevation taken on the line 17—17 in Fig. 2. And Fig. 18 is an enlarged detail view of the engine controlling switch mechanism shown in Fig. 1.

In carrying the invention into effect, there is provided an air tank, a pressure pump in communication with the tank and automatically operative connections co-operating with the pump whereby said pump is caused to maintain a pre-determined pres-

sure within the tank. There is further provided a motor in communication with the tank, operative connections whereby the motor causes rotation of an engine crankshaft, and automatically operative connections co-operating with the motor whereby said motor is thrown out of action when pressure within the tank falls to a pre-determined minimum. There is further provided a speed changing mechanism, a starting device, and means co-operating with said mechanism and device whereby neither said mechanism nor said device can be operated while the other is in operation or in position for operation.

In the best constructions, the starting device will be inbuilt with the speed changing mechanism and so arranged that the lubricating of the speed changing mechanism also lubricates the starting mechanism without further attention; and for the further reason that the weight of the device as a whole is thereby reduced and the starting mechanism may or may not be employed as desired. In the best constructions also the starting device will include a convertible pressure pump and engine starting motor, both being automatically connected at the proper times with the main driving mechanism of the automobile in connection with which the device is used. In the best constructions also the device will be equipped with an air storage tank, a conduit in communication with the tank, means co-operating with the conduit for normally permitting a flow of air under pressure through the conduit toward the tank only, and mechanism co-operating with the conduit whereby air under pressure is permitted to flow temporarily from the tank. In the best constructions also the device will be provided with a connection whereby the starting motor operates the controlling switch of the engine ignition system when through carelessness it has been left in inoperative position. In the best constructions also there will be provided a speed changing mechanism, an engine starting mechanism and a single operating member controlling the action of both mechanisms. In the best constructions also there will be provided a shock absorbing clutch interposed between the starting device and speed changing mechanism and the crankshaft. All of the various elements of the mechanisms and devices above referred to may be varied in construction within wide limits.

The device selected to illustrate the invention constitutes one of many possible concrete embodiments of the invention but it is to be understood that wide structural variations may be made in carrying the invention into effect.

Referring particularly to Fig. 1, the reference character 1 indicates a chassis of well-

known construction having among other elements a pair of sub-frames 2 supported by the main frame in a well-known manner which needs no description herein. Supported upon the sub-frames 2 is a combined speed changing mechanism and convertible pressure pump and engine starting motor all incased in a housing generally indicated at 3, bolted to the sub-frames. A conduit 4 leads from the housing 3 to an air storage tank 5 secured by means of straps 6 to the main frame of the chassis. The engine which drives the chassis is located within the hood 7 and is provided with a flywheel 8. Coöoperating with the flywheel 8 is a shock absorbing clutch 9, the purpose of which is to absorb the shock due to sudden changes in the relative speeds of the engine and speed changing gearing. This shock absorbing clutch is fully disclosed in Patents No. 1049531 and No. 1049532, issued January 7, 1913, and reference is made to said patents for a full disclosure of this clutch. A detailed description of the clutch is therefore omitted herefrom in the interest of brevity.

Mounted upon a dash 10 is a switch 11 of the well-known Bosch type which is provided with a lug 12 arranged to be kicked by the driver in and out of operative position. This switch controls the ignition system for exploding charges of gas in the cylinders of the engine in a well-known manner. For the purpose of connecting this switch with the engine starting device there is provided a lug 13 riveted or otherwise fastened to the switch 11, and to this lug is attached a cable 14. This cable runs through a pulley 15 suitably supported upon the dash 40 and extends rearwardly to one of the controlling members of the engine starting device. The housing generally indicated by the reference character 3 in Fig. 1 is made up of three sections; the lower section being marked 16, the middle section being marked 17 and the upper section being marked 18. The lower and middle sections are split in the horizontal plane including the axis of the main drive of the machine and are bolted together in a manner well-known in the art. The middle section 17 serves as a spacer separating the lower and upper sections and extends to a horizontal plane above the speed changing mechanism. The upper and middle sections are bolted together in a manner well-known in the art and clearly illustrated in the drawings. The lower and middle sections support at the forward end of the housing a ball bearing 19 of well-known construction; at the rear end of the housing a double ball bearing 20 also of well-known construction; and between the two a third ball bearing 21. The bearings 19 and 21 support a shaft 22 which derives its motion 65 from the engine through the agency of the

clutch 9. This shaft carries at its rear end a driving pinion 23 having projecting therefrom dogs 24. This pinion 23 is in constant mesh with a gear 25 bolted to a flange 26 forged on a countershaft 27 which is journaled in ball bearings 28 and 29 of well-known construction. This countershaft is provided with a second flange 30 to which is bolted a gear 31. Keyed to the countershaft 27 between the gear 31 and the bearing 29 is a sleeve 32 having integral gears 33 and 34. The gear 34 is in mesh with an idle gear 35 mounted to rotate upon a stud 36 fast to the end of the lower section 16 of the housing. The rear end of the shaft 22 is reduced in diameter and runs in bushes 37 and 38 fast in a tail shaft 39 which incloses the rear end of the shaft 22. This tail shaft 39 projects through and is supported by the bearings 20. A series of balls 40 is interposed between the rear end of the shaft 22 and a disk 41 carried by the hollow part of the shaft 39. These balls are for the purpose of minimizing end thrust friction between the two shafts. Splined upon the shaft 39 between the pinion 23 and the bearings 20 is a gear 42 adapted to slide into mesh with the gear 33 or with the idler 35, which idler is the reverse gear of the train. Similarly splined upon the shaft 39 is another gear 43 adapted for engagement with the gear 31. This gear 43 has dogs 44 on its forward face adapted for engagement with the dogs 24 of the pinion 23. The gear 42 is engaged by a shifting arm 45 fast upon and moved by a shifting rod 46. Similarly the gear 43 is engaged by a gear shifting arm 47 fast upon and moved by a gear shifting rod 48. The rod 46 is provided with depressions 49 and the rod 48 is similarly provided with depressions 50. The depressions 49 of the rod 46 are adapted to be engaged (see Fig. 8) by a ball 51 held in place by means of a spring 52 working in a socket 53 extending upwardly from a bearing 54 in which the forward end of the rod slides. The upper end of the socket 53 is closed by means of a screw plug 55. The function of the ball 51 is to hold the rod 46 against accidental movement. When, however, the rod is moved intentionally, the ball rises from its seat and in one of the depressions and rides along the top of the rod until another depression comes into register with it. The depressions 50 of the rod 48 are similarly engaged by a ball which is a duplicate of the ball 51 and mounted in the same manner. The rod 46 is provided at a point adjacent the depressions 49 with a V-shaped recess 56. Similarly the shifter rod 48 is provided with a V-shaped recess 57 normally located opposite the recess 56. Between the two is located a ball 58. When either of the shifter rods is moved from its neutral position, as shown in Fig. 7, the ball 130

is forced into the recess of the other shifter rod and in coöperation with the bearing 54 serves as a positive lock to prevent displacement of the other shifter rod until the one moved is again brought to neutral position. The rod 46 is further provided with a fork 59 and the rod 48 is similarly provided with a fork 60. These forks are adapted to be engaged by a lever 61 which is keyed upon a sleeve 62. This sleeve 62 is journaled in a bearing 63 the lower half of which is formed by a part of the mid-section 17 of the housing and the upper part of which is formed by a cap 64 bolted to the mid-section of the housing. The sleeve 62 extends to a point beyond the right side of the chassis and within said sleeve is mounted a hollow shaft 65. This hollow shaft 65 is journaled in the sleeve and in a bearing 66 formed in part by the mid-section of the housing and in part by the cap 64. Upon the projecting end of the hollow shaft 65 is secured a lever 67 from which a connection not shown may be led to the emergency brakes. The opposite end of the hollow shaft 65 projects beyond the sleeve 62 and carries a lever 68 by means of which it is operated. The hub of the lever 68 is journaled in a bearing 69 formed on a bracket 70 bolted to and extending from the outside of the chassis 1. The sleeve 62 is provided with a lever 71 upstanding therefrom at a point adjacent the lever 68. Extended from the bearing 69 is a yoke 72 which carries upon its outer side a sector bar 73 which guides the brake lever 68. The yoke further carries a slotted sector 74 in which the gear shifting lever 71 operates. This sector 74 is provided with two recesses on its forward side and three on its rear side. The recess marked H indicates the position of the lever 71 when the speed changing mechanism is in high gear. The recess marked I indicates the position of the lever 71 when the speed changing mechanism is in intermediate gear. The recess marked L indicates the position of the lever 71 when the speed changing mechanism is in reverse gear.

The mechanism so far described is old and well known in the art and it will be readily understood that the lever 71 with the sleeve 62 may be moved longitudinally to throw the lever 61 from engagement with the shifter rod 48 to the shifter rod 46. In the present device, however, the sleeve has an additional movement, as indicated in Figs. 2, 9 and 17; and by an inspection of Fig. 2, 60 it will be readily understood that the lever 71 cannot be moved to the third position and into the recess marked S until the lever 61 has moved from the position shown in full lines in Fig. 9 past the position where 65 it engages with the fork 59 of the shifter

rod 46 and to a third position where it is clear of both shifter rods so that it is impossible to move the lever 71 into the recess marked S until the speed changing mechanism has been left locked in neutral position, 70 and the construction of the recess S is such that the lever 71 cannot be moved out from said recess without going to the neutral position. The recess S indicates the position of the lever 71 when the starting device to be 75 hereinafter explained is in operation.

There is provided a pressure pump in communication with the tank and automatically operative connections coöperating with the pump whereby said pump is caused to maintain a pre-determined pressure within the tank. With this end in view, the conduit 4 leading to the tank 5 is connected by means of a union 75 with a passage 76 (see Figs. 14 and 15), which passage leads to a 80 chamber 77 formed in a casting 78, which casting is bolted to the upper section 18 of the housing and which serves as a cylinder head for the pump and motor and controlling connections to be hereinafter described. 85 There are provided four cylinders 79, 80, 81 and 82 which are formed of steel tubing incased in the upper section 18 of the housing. Each of these cylinders is provided with a series of apertures 83 formed in the walls 90 thereof and affording open communication between the interior of the cylinder and the interior of the upper section 18 of the housing (see Fig. 16) when the piston within the cylinder is in its lowermost position. The 95 space between the walls of the upper section 18 of the housing and the walls of the cylinders is open to the atmosphere through a breathing screen 84 located in and secured to one end of the casting 78. Each of the 100 cylinders 79, 80, 81 and 82 is provided with a piston 85 and each piston is provided with a cupped leather packing 86 held in place by means of a nut 87 of well-known construction. Each of the pistons is further 105 provided with a wrist pin 88 upon which is mounted one end of a connecting rod 89, the other end of which is connected to one of the cranks of a crankshaft 90. This crankshaft 90 is supported in bearings 91 depending from the upper section 18 of the housing. The particular construction of these cylinders, pistons and cranks is well known in the art and a more detailed description thereof is therefore omitted in the interest 110 of brevity. The casting 78 is provided with 115 4 ports 92, one for each of the cylinders 79, 80, 81 and 82. These ports extend from the interior of their respective cylinders to the interior of the chamber 77 before referred to, and each port is normally closed by a ball check valve 93 (see Fig. 11) which is normally held upon its seat by means of a spring 94 incased in a tube 95, which tube 120 is extended from the bottom of a plug 96 125 130

threaded in a suitable aperture in the casting 78 immediately over the port 92. In the operation of the pistons and cylinders, as a pressure pump, when any particular piston 5 has reached a point adjacent its lowermost position, it has created a partial vacuum within its cylinder. As the downwardly moving piston uncovers the apertures 83 in the cylinder walls air from the chamber 10 formed by the walls of the upper section 18 of the housing and coming through the breathing screen 84 rushes into the cylinder and completely fills the same. When the piston moves upwardly it compresses the air 15 within the cylinder and when the pressure within the cylinder overbalances the pressure within the chamber 77, the conduit 4 and the tank 5, the ball check valve 93 is lifted and the compressed air passes from 20 the cylinder into the chamber 77 and thence into the conduit 4 and tank 5.

While any suitable means may be employed to operate the crankshaft of the pressure pump and thereby operate the 25 pump, in the device selected to illustrate the invention the crankshaft 90 is operated automatically by the following mechanism: Keyed upon the shaft 22 (see Fig. 5) is a friction clutch member 97 and slidably 30 mounted upon said shaft 22 between the clutch member 97 and the bearing 19 is a co-operating clutch member 98. This clutch member 98 carries a pinion 99 which is in mesh with a gear 100 keyed upon an extension 35 of the shaft 90 which is journaled in bearings 101 and 102 depending from the upper section 18 of the housing and in alignment with the bearings 91. The clutch member 98 is engaged by one end of a forked 40 bell-crank 103 which is fulcrumed upon a pin 104 mounted in the lower end of the bearing 101. The free end of this bell-crank lever carries a pin 105 to which is pivoted one end of a connecting rod 106 45 which is forked to straddle the shaft 90. The upper end of the connecting rod 106 is pivoted to a wrist pin 107 secured to a piston 108 which piston is similar in all respects to the pistons 85 of the pressure 50 pump. The piston 108 is mounted in a cylinder 109 formed in the same manner as the cylinders 79, 80, 81 and 82 but without the wall ports 83. The piston 108 is normally held in its uppermost position by the 55 action of a spring 110 located within the cylinder below the piston and this piston constantly tends through the agency of the connecting rod 106 and forked bell-crank 103 to keep the clutch member 98 in frictional engagement with the clutch member 97. The upper end of the cylinder 109 is closed by a flexible gasket 111 so that no air can pass into the cylinder 109 above the piston 108. Immediately over the center of 60 the cylinder 109 the casting 78 is provided

with a recess 112 from which a port 113 leads to a valve chamber which extends across the top of all of the cylinders. Within this chamber is located a valve 114 which is rotatably and slidably mounted within the 70 valve chamber. The means for rotating and for sliding the valve will be hereinafter described. In the normal operation of the device the valve 114 occupies the position shown in Fig. 5 and when the valve is in this 75 position an annular channel 115 formed therein lies immediately over the port 113. In the side wall of the valve chamber adjacent the chamber 77 (see Fig. 14) there is located a port 116 which registers with the 80 annular channel 115 when the valve is in its normal position; that is, in the position shown in Fig. 5 and not in the position shown in Fig. 14. By this construction it will be readily understood that pressure 85 within the tank, the conduit 4 and the chamber 77 will be communicated through the port 116, the annular channel 115 and the port 113 to the recess 112 above the flexible gasket lying at the top of the piston 108. 90 It will therefore be readily understood that when the pressure within the tank and consequently within the conduit 4 and chamber 77 is great enough to overcome the upward thrust of the spring 110, the piston 108 will be forced downwardly by the air pressure and through the agency of the connecting rod 106 and the bell-crank 103 will throw the clutch member 98 out of engagement with the clutch member 97 and thereby 95 stop the pressure pump. It will be readily understood also that whenever the pressure within the tank and above the piston 108 falls below the degree controlled by the strength of the spring 110, the spring will 100 again force the piston 108 upward and through its operating connections throw the clutch member 98 into engagement with the clutch member 97. The pinion 99 and gear 100 are so proportioned that when the 105 engine of the automobile is running at its most efficient speed, the pressure pump will also run at its most efficient speed; and since the clutch members 97 and 98 operate by friction, it will be readily understood 110 that they will go into action without shock and danger of breakage of any of the parts of the pressure pump irrespective of the speed at which the engine happens at the moment to be running. It will be noted that 115 the shaft 22 is a driving element common both to the pressure pump and to the speed changing mechanism which constitutes a part of the main driving mechanism of the automobile in connection with which the device is used. 120

It will be readily understood that by the construction just described and by an inspection of Fig. 5, the entire pressure pump may be removed by lifting the upper section 130

18 of the housing from the middle section 17. It is well known that speed changing gearing runs in a liberal bath of lubricant and that this lubricant is splashed all over 5 the inside of the housing in which the gearing is mounted. This splashing action serves to throw lubricant up around the crankshaft 90 and into the cylinders 79, 80, 81 and 82, thereby lubricating the same 10 without any special lubricating devices. For the purpose of retaining a portion of 15 this splashed lubricant on the various cranks and bearings of the pressure pump, each of the bearings and connecting rods 15 and cranks is provided a cup 117 from which passages 118 lead to the main shaft bearings and the cranks of the shaft.

For the purpose of retaining the air under pressure within the tank 5 and conduit 4 20 while the automobile in connection with which the device is used is standing idle for any length of time, there is provided means cooperating with the conduit for normally permitting a flow of air under pressure 25 through the conduit toward the tank only, and mechanism cooperating with the conduit whereby air under pressure is permitted to flow temporarily from the tank. In the device selected to illustrate the invention this means includes a valve 119 (see 30 Figs. 13 and 15) having a stem 120 mounted to slide in a suitable boss formed on the casting 78 before referred to. This valve is normally seated at the entrance of the 35 passage 76 before referred to and is held against its seat by means of a spring 121 located within the union 75 before referred to. While this spring is light so that it does not interfere with compressed air passing 40 from the chamber 77 to the conduit 4 its tension is sufficient to properly seat the valve at all other times; and when the automobile in connection with which the device is used is standing idle, the tank pressure 45 aids the spring in keeping the valve 119 closed tightly to prevent any loss of pressure. Means are provided for mechanically unseating the valve 119 when it is desired to permit air under pressure to flow 50 from the tank to the chamber 77. This means, in the device selected to illustrate the invention, includes a controlling member which controls not only the flow of air from the tank, but also controls a valve 55 which operates to convert the pressure pump into a motor with suitable connections for starting the engine of the automobile in connection with which the device is used. This controlling member consists of 60 a slidable plunger 122 mounted in the casting 78 before referred to and in a cap 123 bolted to the forward end of said casting (see Figs. 6 and 5). Its rear end is reduced in diameter and is surrounded by a spring 65 124 which tends to hold the plunger 122 in

the position shown in Fig. 5. The extreme rear end of the plunger 122 is provided with a flat surface 125, an inclined surface 126 and a second flat surface 127 (see Fig. 13). When the parts are in normal position the 70 surface 125 is just clear of the end of the stem 120 of the valve 119 controlling the outlet of air from the tank to the passage 76. When the plunger 122 is moved rearwardly, the stem 120 rides up the inclined 75 surface 126 to the second flat surface 127 thus opening the valve 119 and holding it open as long as the plunger is in its rear-most position; that is, the position shown in Fig. 6. That part of the plunger 122 immediately forward of the spring 124 is provided with a series of expansion grooves 128. These grooves are for the purpose of preventing leakage of air past the plunger which may have leaked past the stem 120 of the valve 119 into the chamber in which the plunger works. It may be here remarked that in the operation of the device the air is drawn from the tank for the purpose of starting the engine for a very short time, 90 usually not more than one second and seldom more than three seconds, so that an absolutely airtight fit of the valve stem 120 and plunger 122 is not required.

The plunger 122 has at a point near its 95 forward end but within the cap 123 a fork 129 which engages and is adapted to slide the valve 114 before referred to. For the purpose of operating or sliding the plunger 122 against the action of the spring 124, the 100 plunger is provided with a recess 130 at a point adjacent its forward end and outside the cap 123. This recess is adapted to be engaged by a lever 131 mounted upon the sleeve 62 before referred to and movable 105 therewith. The lever 131 is so located on the sleeve 62 that it can come into engagement with the plunger 122 only when the lever 71 is in the starting position and the lever 61 is free from the speed changing 110 shifter rods 46 and 48. The rotating movement of the valve is effected in the following manner: Upon the rear end of the crank-shaft 90 is keyed a gear 132 which is in mesh with a gear 133 running idle on a bush 134, which bush is held in place by a tapered stud 135 threaded into a boss forming a part of the upper section 18 of the housing before referred to. The gear 133 is in mesh with a broad faced gear 136. The gear 136 is keyed 115 to the rear end of the valve 114 and remains in mesh with the gear 133 irrespective of the longitudinal position of the valve. When the cylinders 79, 80, 81, and 82 are to be used as a part of a motor for the purpose of starting the engine in connection with which the device is used, the valve 114 controls the passage of air from the chamber 77 to the respective cylinders. With this end in view, the wall separating 120 125 130

the valve chamber from the chamber 77 is provided with ports 137, 138, 139 and 140 respectively adapted to permit the passage of air to the cylinders 79, 80, 81 and 82. 5 The cylinder 79 is provided with an intake port 141 and an exhaust port 142. Similarly, the cylinder 80 is provided with an intake port 143 and an exhaust port 144. Similarly, the cylinder 81 is provided with 10 an intake port 145 and an exhaust port 146. And similarly, the cylinder 82 is provided with an intake port 147 and an exhaust port 148. Upon the side of the casting 78 opposite the chamber 77 is an exhaust chamber 149 open at one end to the atmosphere through the breathing screen 84 before described. Ports are cut in the wall between the chamber 149 and the valve chamber to permit egress of exhaust air into the chamber 149. These ports are numbered 150, 151, 152 and 153 and are respectively in the same transverse plane as the exhaust ports 142, 144, 146 and 148 of the cylinders, while the valve chamber ports 137, 138, 139 and 140 20 are respectively in the same transverse plane as the intake ports 141, 143, 145 and 147 of the cylinders. The valve 114 is provided with semi-circumferential channels 154, 155, 156 and 157 which are located in the same 25 transverse plane as the intake ports of the cylinders only when said cylinders are in operation as a motor. Similarly, the valve 114 has a series of semi-circular exhaust channels 158, 159, 160 and 161 which are in 30 the same transverse plane as the exhaust ports of the cylinders only when said cylinders are operating as a motor; that is to say, when the valve is in the position shown in Figs. 6 and 14. The intake channels of 35 the valve are arranged to open the ports of their respective cylinders at the beginning of the stroke and to cut off the communication at approximately five-eighths of the downward stroke of the piston. When any 40 particular piston has completed about seven-eighths of its down stroke, it uncovers the wall ports 83 of its cylinder and the air within the cylinder blows out through said ports into the chamber formed by the upper 45 section 18 of the housing and thence to the atmosphere through the breathing screen 84, the housing serving as a muffler to deaden 50 the noise of the exhaust. When the piston begins its upward movement, it closes the wall ports 83 and imprisons some air within 55 the cylinder at about atmospheric pressure. This air passes out through the exhaust ports into the chamber 149 and thence to the atmosphere, the circumferential exhaust 60 channels of the valve 114 being arranged to leave the cylinder open to the exhaust until the piston reaches a point close to its uppermost point, a little air being left in the cylinder at the time to insure quicker and 65 smoother action when the compressed air

comes through the intake port. By an inspection of Figs. 10 and 12, it will be seen that the intake and exhaust ports leading from the valve chamber are below the axis of the valve. For the purpose of insuring the 70 proper seating of the valve with respect to the intake and exhaust ports, there are provided passages 162 (see Figs. 5, 6 and 11), which passages open into the chamber 77 and extend over the top of the valve 114. 75 The pressure in these passages tends to keep the valve 114 properly seated at the entrances to the intake and exhaust ports.

To prevent leakage of air from any one circumferential intake channel to an adjacent exhaust channel in the valve, there is 80 provided a series of expansion grooves 163 located between adjacent channels.

It will be remembered that the clutch member 98 is held out of contact with the 85 clutch member 97 only when the pressure within the tank and within the cylinder 109 is sufficient to overcome the action of the spring 110. When it is desired to operate the device as a motor, it is necessary to imprison the air under pressure within the cylinder 109 and above the gasket 111 so that the pressure therein will not fall while the pressure within the tank is falling as the 90 motor operates. By an inspection of Fig. 95 14, it will be readily understood how this is accomplished by a mere sliding of the valve 114 which throws the annular channel 115 out of alignment with the cylinder port 113 and the valve chamber port 116. This same 100 movement brings an annular channel 164 formed in the valve into register with a port 165 (see Figs. 5 and 6) communicating with a cylinder 166 similar in all respects to the cylinder 109 and inclosing a piston 167 similar in all respects to the piston 108 before referred to. The flexible gasket 111 extends over this cylinder also. When the valve is moved to the position shown in Fig. 6, the 105 channel 164 is in register with the port 165 and with a port 168 (see Fig. 14) leading to the chamber 77. It will, therefore be readily understood that when the valve reaches the position shown in Fig. 6, air will 110 enter the cylinder 166 above the gasket and force the piston 167 down against the action of the spring 169 incased within the cylinder below the piston. The piston 167 carries a wrist pin 170 to which is pivoted one 115 end of a forked connecting rod 171 which straddles the crankshaft 90. The lower end of the connecting rod 171 is pivoted to a pin 172 mounted on one of the arms of a forked bell-crank lever 173. This bell-crank lever is fulcrumed on a pin 174 which pin is 120 mounted on the lower part of the bearing 102 before referred to. The lower end of the bell-crank lever 173 engages a clutch 175 which is slidably mounted upon the shaft 22 before referred to. Keyed upon the shaft 125 130

22 is another clutch member 176 adapted to coöperate with the member 175. The clutch member 175 has a gear cut on its periphery which meshes with a pinion 177 keyed upon 5 the crankshaft 90 adjacent the bearing 102. The arrangement of the pinion 177 and the geared clutch member 175 is such that the air motor runs at its most efficient speed when turning the crankshaft of an engine at 10 the proper speed for starting purposes. It may sometimes happen that a driver will throw in a motor and keep it in after the engine had started and attained high speed which might result in injury to the starting device due to the ratio of the connecting 15 gears and would certainly result in exhausting all the compressed air from the tank. To prevent such action the tension of the spring 169 is regulated to overcome the air pressure in the cylinder 166 above the gasket 111 when a pre-determined minimum pressure has been reached. When this predetermined minimum pressure has been reached, the spring 169 will, through its various 20 connections, throw the clutch member 175 out of engagement with the clutch member 176 no matter where the valve is. When this happens air will be wasted; but since the clutch members are out of engagement 25 the more powerful engine will not injure the motor. When the engine has been started and it is desired to stop the starting motor, the valve 114 is moved back to its normal position in which all of its intake 30 and exhaust channels are out of register with their respective cylinders, intake and exhaust ports. This brings the annular channel 115 again into register with the port 113 of the cylinder 109 and into register with the port 116 leading to the chamber 77. At this time it will be remembered 35 that air under maximum pressure was imprisoned in the cylinder 109 to hold the pressure pump clutch out of operation before the starting action took place. After 40 the starting action took place the pressure within the chamber 77 fell. Consequently as soon as the valve again brings its channel 45 115 into communication with the cylinder 109 and chamber 77, the pressure within the cylinder will instantly drop to that within the chamber 77. This permits the spring 50 110 to again act automatically to throw the clutch members 97 and 98 into engagement and cause the pump to immediately begin to restore the pressure to the maximum; in other words, the first thing that 55 happens after the engine has been started is the restoration of the pressure in the tank 60 no matter whether the automobile in connection with which the device is used is standing idle or running at any rate of speed.

For the purpose of relieving the pressure

within the cylinder 166 when the starting 65 action ceases, there is provided a relief port 178 in the head of the cylinder 166, which port is in register with the valve channel 164 when said channel is returned to its normal position. When in this position the 70 channel 164 is also in register with the relief exhaust port 179 leading to the exhaust chamber 149 before referred to. This insures the disengagement of the clutch members 75 97 and 98 are thrown into engagement at the instant the valve is returned to its normal position after the starting operation.

For the purpose of facilitating inspection 80 of the speed changing gearing, there is provided a manhole plate 180 held by means of thumb screws to the mid-section of the housing and for the purpose of facilitating the inspection of the clutch mechanism of the convertible pressure pump and motor there 85 is provided a similar manhole plate 181 also held in place by means of thumb screws in a well-known manner.

It will be readily understood that since the device is automatically lubricated by the 90 lubricating system of the speed changing mechanism, and since air is to be found wherever the automobile may be, and since the pressure pump is entirely automatic in its action to maintain a pressure within the 95 tank, no attention upon the part of the driver is required except at the instant he desires to start the motor, and then the only action required is an additional movement of a lever which he must move before he can 100 start his car. It will be readily understood also that since the starting motor is a four-cylinder motor, it has no dead center; and since the connection between the starting motor and the engine is through the clutch 105 and crankshaft, it is immaterial whether the engine is on dead center or not.

In view of the foregoing, a detailed description of the operation of the device is deemed unnecessary and is therefore omitted in the interest of brevity and clearness. 110

What is claimed is:

1. In an engine starting device, the combination with an air tank, of an engine crankshaft, power transmission mechanism clutched to and operated by said engine crankshaft, a pressure pump independent of but inbuilt with said transmission mechanism and in communication with said tank, and automatically operative connections co-operating with the pump and transmission mechanism whereby said pump is caused to maintain a predetermined pressure within the tank. 115

2. In an engine starting device, the combination with an air tank, of an engine crankshaft, power transmission mechanism clutched to and operated by said engine 120

125

- crankshaft, a pressure pump independent of but inbuilt with said transmission mechanism and in communication with said tank, automatically operative connections coöperating with the pump and transmission mechanism whereby said pump is caused to maintain a predetermined pressure within the tank, and means for temporarily holding said connections out of action.
10. 3. In an engine starting device, the combination with an air tank, of an engine crankshaft, power transmission mechanism clutched to and operated by said engine crankshaft, a pressure pump independent of but inbuilt with said transmission mechanism and in communication with said tank, and automatically operative connections coöperating with the pump and transmission mechanism and controlled by pressure from the tank whereby said pump is caused to maintain a predetermined pressure within the tank.
4. In an engine starting device, the combination with an air tank, of an engine crankshaft, power transmission mechanism clutched to and operated by said engine crankshaft, a pressure pump independent of but inbuilt with said transmission mechanism and in communication with the tank, automatically operative connections coöperating with the pump and transmission mechanism and controlled by pressure from the tank whereby said pump is caused to maintain a predetermined pressure within the tank, and means for cutting off said connections from the tank whereby said connections are temporarily held out of action by pressure.
5. In an engine starting device, the combination with an air tank, of an engine crankshaft, power transmission mechanism clutched to and operated by said engine crankshaft, a pressure pump independent of but inbuilt with said transmission mechanism and in communication with the tank, automatically operative connections coöperating with the pump and transmission mechanism and controlled by pressure from the tank whereby said pump is caused to maintain a predetermined pressure within the tank, and valve mechanism for cutting off said connections from the tank whereby said connections are temporarily held out of action by pressure and for simultaneously opening a conduit whereby air is drawn from the tank.
6. In an engine starting device, the combination with an air tank, of an engine crankshaft, power transmission mechanism clutched to and operated by said engine crankshaft, a pressure pump independent of but inbuilt with said transmission mechanism and in communication with the tank, and automatically operative connections coöperating with the pump and transmission mechanism whereby said pump is caused to maintain a predetermined pressure within the tank, and means for temporarily holding said connections out of action.
7. In an engine starting device, the combination with an air tank, of an engine crankshaft, power transmission mechanism clutched to and operated by said engine crankshaft, a pressure pump independent of but inbuilt with said transmission mechanism and in communication with the tank, and automatically operative connections coöperating with the pump and transmission mechanism and including a spring pressed friction clutch coöperating with said transmission mechanism whereby said pump is caused to maintain a predetermined pressure within the tank.
8. In an engine starting device, the combination with an air tank, of an engine crankshaft, power transmission mechanism clutched to and operated by said engine crankshaft, a pressure pump independent of but inbuilt with said transmission mechanism and in communication with the tank, and automatically operative connections coöperating with the pump and transmission mechanism and including a spring closed friction clutch coöperating with said transmission mechanism and controlled by pressure from the tank whereby said pump is caused to maintain a predetermined pressure within the tank.
9. In an engine starting device, the combination with an air tank, of an engine crankshaft, power transmission mechanism clutched to and operated by said engine crankshaft, a pressure pump independent of but inbuilt with said transmission mechanism and in communication with the tank, and automatically operative connections coöperating with the pump and transmission mechanism and including a friction clutch coöperating with said transmission mechanism and also including a spring pressed and pressure controlled member for controlling the action of the clutch whereby said pump is caused to maintain a predetermined pressure within the tank.
10. In an engine starting device, the combination with an air tank, of an engine crankshaft, power transmission mechanism clutched to and operated by said engine crankshaft, a pressure pump independent of but inbuilt with said transmission mechanism and in communication with the tank, and automatically operative connections coöperating with the pump and transmission mechanism and including a friction clutch coöperating with the transmission mechanism and also including a cylinder and a spring pressed and pressure controlled piston

within the cylinder for controlling the action of the clutch whereby said pump is caused to maintain a predetermined pressure within the tank.

6 11. In an engine starting device, the combination with an air tank, of a motor in communication with the tank, operative connections whereby the motor causes rotation of an engine crankshaft, and automatically 70
10 operative connections coöperating with the motor whereby said motor is thrown out of action when pressure within the tank falls to a predetermined minimum.

12. In an engine starting device, the combination with an air tank, of a motor in communication with the tank, operative connections whereby the motor causes temporary rotation of an engine crankshaft, automatically operative connections coöperating 75
15 with the motor whereby said motor is thrown out of action when pressure within the tank falls to a predetermined minimum, and means for normally holding said automatically operative connections out of action.

20 25. 13. In an engine starting device, the combination with an air tank, of a motor in communication with the tank, operative connections whereby the motor temporarily causes rotation of an engine crankshaft, and 80
30 automatically operative connections coöperating with the motor and controlled by pressure from the tank whereby said motor is thrown out of action when pressure within the tank falls to a predetermined minimum.

35 35. 14. In an engine starting device, the combination with an air tank, of a motor in communication with the tank, operative connections whereby the motor causes temporary rotation of an engine crankshaft, automatically operative connections coöperating 85
40 with the motor and controlled by pressure from the tank whereby said motor is thrown out of action when pressure within the tank falls to a predetermined minimum, and 90
45 means for cutting off said automatically operative connections from the tank whereby said connections are normally held out of action.

15. In an engine starting device, the combination with an air tank, of a motor in communication with the tank, operative connections whereby the motor causes temporary rotation of an engine crankshaft, automatically operative connections coöperating 95
50 with the motor and controlled by pressure from the tank whereby said motor is thrown out of action when pressure within the tank falls to a predetermined minimum, and valve mechanism for cutting off said automatically 100
55 operative connections from the tank whereby said connections are normally held out of action.

60 16. In an engine starting device, the combination with an air tank, of a motor in communication with the tank, operative con- 105
65

nections whereby the motor causes rotation of an engine crankshaft, and automatically operative connections coöperating with the motor and including a friction clutch whereby said motor is thrown out of action when pressure within the tank falls to a predetermined minimum.

70 17. In an engine starting device, the combination with an air tank, of a motor in communication with the tank, operative connections whereby the motor causes rotation of an engine crankshaft, and automatically operative connections coöperating with the motor and including a spring opened friction clutch whereby said motor is thrown out of action when pressure within the tank falls to a predetermined minimum.

75 18. In an engine starting device, the combination with an air tank, of a motor in communication with the tank, operative connections whereby the motor causes rotation of an engine crankshaft, and automatically operative connections coöperating with the motor and including a spring opened friction clutch controlled by pressure from the 80
85 tank whereby said motor is thrown out of action when pressure within the tank falls to a pre-determined minimum.

90 19. In an engine starting device, the combination with an air tank, of a motor in communication with the tank, operative connections whereby the motor causes rotation of an engine crankshaft, and automatically operative connections coöperating with the motor and including a friction clutch and a 95
95 spring pressed and pressure controlled member for controlling the action of said clutch whereby said motor is thrown out of action when pressure within the tank falls to a pre-determined minimum.

100 20. In an engine starting device, the combination with an air tank, of a motor in communication with the tank, operative connections whereby the motor causes rotation of an engine crankshaft, and automatically 105
110 operative connections coöperating with the motor and including a friction clutch and a cylinder and a spring pressed and pressure controlled piston within the cylinder for controlling the action of said clutch whereby 115
115 said motor is thrown out of action when pressure within the tank falls to a pre-determined minimum.

120 21. The combination with speed changing mechanism, of a power operated engine starting device, and a single movable member and operative connections for selectively actuating either said mechanism or said device and for preventing operation of either when the other is in operation.

125 22. The combination with speed changing mechanism, of a power operated engine starting device, and a single movable member and operative connections interlockable with said mechanism and said device for 130

- selectively actuating either said mechanism or said device and for preventing operation of either when the other is in operation.
23. The combination with speed changing mechanism, of a power operated engine starting device having a controlling member, and a single movable member and operative connections interlockable with said speed changing mechanism and with the controlling member of said starting device for selectively actuating either said mechanism or said device and for preventing operation of either when the other is in operation.
- 10 24. The combination with speed changing mechanism, of a starting device having a controlling member, and interlockable connections between said mechanism and said member and carried by the speed changing mechanism whereby neither said mechanism nor said device can be operated while the other is in operation.
- 15 25. The combination with speed changing mechanism having a movable member, of a starting device having a notched controlling member, and interlockable connections carried by the movable member of the speed changing mechanism and adapted for engagement with the notch of the controlling member whereby neither said mechanism nor said device can be operated while the other is in operation.
- 20 26. The combination with speed changing mechanism having an oscillatory member, of a starting device having a notched slideable controlling member, and interlockable connections carried by the oscillatory member and adapted for engagement with the notch of the controlling member whereby neither said mechanism nor said device can be operated while the other is in operation.
- 25 27. The combination with speed changing mechanism having a slideable and oscillatory member, of a starting device having a controlling member, and interlockable connections between said members whereby neither said mechanism nor said device can be operated while the other is in operation.
- 30 28. The combination with speed changing mechanism having a slideable and oscillatory member, of a starting device having a controlling member, interlockable connections between said members, and means for selectively operating the slideable and oscillatory member of the speed changing mechanism to operate either said mechanism or said starting device.
- 35 29. The combination with speed changing mechanism having a slideable and oscillatory member, of a starting device having a controlling member, interlockable connections between said members, and a lever connected with the slideable and oscillatory member of the speed changing mechanism for selectively operating the slideable and oscillatory mem-
- ber of the speed changing mechanism to operate either said mechanism or said starting device.
30. The combination with speed changing mechanism having a slideable and oscillatory member, of a starting device having a notched slideable controlling member, an arm fixed upon and movable with the slideable and oscillatory member of the speed changing mechanism said arm being adapted for intermittent engagement with the notch of the slideable controlling member, a lever fixed to the slideable and oscillatory member of the speed changing mechanism, and means for guiding the lever and adapted to prevent operation of either the speed changing mechanism or the starting device when the other is in operation.
- 70 31. The combination with speed changing mechanism, of a starting device independent of but inbuilt with said mechanism, a single operating member controlling the action of said mechanism and said device, a movable member common to said mechanism and device, and operative connections whereby said movable member temporarily rotates the crankshaft of an engine.
- 75 32. The combination with speed changing mechanism, of a starting device independent of but inbuilt with said mechanism, a single operating member controlling the action of said mechanism and said device, a movable member common to said mechanism and device, and operative connections including said movable member and the crankshaft of an engine.
- 80 33. The combination with speed changing mechanism, of a starting device independent of but inbuilt with said mechanism, a single operating member controlling the action of said mechanism and said device, a rotatable shaft common to said mechanism and device, and operative connections whereby said shaft temporarily rotates the crankshaft of an engine.
- 85 34. The combination with speed changing mechanism, of a starting device independent of but inbuilt with said mechanism, a single operating member controlling the action of said mechanism and said device, a rotatable shaft normally operating as a driving shaft for the speed changing mechanism and adapted for intermittent operation as the driven shaft of the starting device, and operative connections whereby said shaft rotates the crankshaft of an engine when operating as the driven shaft of the starting device.
- 90 35. The combination with speed changing mechanism, of a multi-cylinder starting device inbuilt with said mechanism, a shaft normally operating as a driving shaft for the speed changing mechanism and adapted for intermittent operation as the driven shaft of the starting device, operative connections
- 95 100 105 110 115 120 125 130

- between the cylinders of the starting device and said shaft, and operative connections whereby said shaft rotates the crankshaft of an engine when operating as the driven shaft of the starting device.
36. The combination with speed changing mechanism, of a multi-cylinder starting device inbuilt with said mechanism, a shaft normally operating as a driving shaft for the speed changing mechanism and adapted for intermittent operation as the driven shaft of the starting device, operative connections between the cylinders of the starting device and said shaft including a friction clutch, and operative connections whereby said shaft rotates the crankshaft of an engine when operating as the driven shaft of the starting device.
37. The combination with speed changing mechanism, of a multi-cylinder starting device inbuilt with said mechanism, a shaft normally operating as a driving shaft for the speed changing mechanism and adapted for intermittent operation as the driven shaft of the starting device, operative connections between the cylinders of the starting device and said shaft including a spring pressed and pressure controlled friction clutch, and operative connections whereby said shaft rotates the crankshaft of an engine when operating as the driven shaft of the starting device.
38. The combination with speed changing mechanism, of a multi-cylinder starting device inbuilt with said mechanism, a shaft normally operating as a driving shaft for the speed changing mechanism and adapted for intermittent operation as the driven shaft of the starting device, operative connections between the cylinders of the starting device and said shaft including a spring pressed and pressure controlled two-part friction clutch one part being fast upon said shaft, and operative connections whereby said shaft rotates the crankshaft of an engine when operating as the driven shaft of the starting device.
39. The combination with speed changing mechanism, of a multi-cylinder starting device inbuilt with said mechanism, a shaft normally operating as a driving shaft for the speed changing mechanism and adapted for intermittent operation as the driven shaft of the starting device, operative connections between the cylinders of the starting device and said shaft including a spring pressed and pressure controlled two-part friction clutch one part being fast upon said shaft and the other part running loose upon said shaft and being in constant engagement with one of the moving parts of the starting device, and operative connections whereby said shaft rotates the crankshaft of an engine when operating as the driven shaft of the starting device.
40. The combination with speed changing mechanism, of a multi-cylinder compressed air starting device inbuilt with said mechanism, a shaft normally operative as a driving shaft for the speed changing mechanism and adapted for intermittent operation as the driven shaft of the starting device, operative connections between the cylinders of the starting device and said shaft and including a plurality of pistons and connecting rods and a crankshaft geared to a friction clutch member fast upon said shaft, a pressure operated and spring resisted piston and operative connections whereby the clutch members are thrown into engagement when the starting device is to be operated, and operative connections whereby said shaft rotates the crankshaft of an engine only when said clutch members are in engagement.
41. The combination with speed changing mechanism, of a pressure pump independent of but inbuilt with said mechanism, a movable member common to said mechanism and pump, and operative connections whereby the crankshaft of an engine rotates said movable member.
42. The combination with speed changing mechanism, of a pressure pump independent of but inbuilt with said mechanism, a movable member common to said mechanism and pump, and operative connections including said movable member and the crankshaft of an engine.
43. The combination with speed changing mechanism, of a pressure pump independent of but inbuilt with said mechanism, a rotatable shaft common to said mechanism and pump, and operative connections whereby the crankshaft of an engine operates said rotatable shaft.
44. The combination with speed changing mechanism, of a pressure pump inbuilt with said mechanism, a rotatable shaft normally operating as a driving shaft for the speed changing mechanism and adapted for intermittent operation as the driving shaft of a pressure pump, and operative connections whereby the crankshaft of an engine operates said rotatable shaft.
45. The combination with speed changing mechanism, of a multi-cylinder pressure pump inbuilt with said mechanism, a shaft normally operating as a driving shaft for the speed changing mechanism and adapted for intermittent operation as the driving shaft of the pressure pump, operative connections between the cylinders of the pressure pump and said shaft, and operative connections whereby the crankshaft of an engine operates said shaft.
46. The combination with speed changing mechanism, of a multi-cylinder pressure pump inbuilt with said mechanism, a shaft normally operating as a driving shaft for the speed changing mechanism and adapted

for intermittent operation as the driving shaft of the pressure pump, operative connections between the cylinders of the pressure pump and said shaft including a friction clutch, and operative connections whereby the crankshaft of an engine operates said shaft.

47. The combination with speed changing mechanism, of a multi-cylinder pressure pump inbuilt with said mechanism, a shaft normally operating as a driving shaft for the speed changing mechanism and adapted for intermittent operation as the driving shaft of the pressure pump, operative connections between the cylinders of the pressure pump and said shaft including a spring pressed and pressure controlled friction clutch, and operative connections whereby the crankshaft of an engine operates said shaft.

48. The combination with speed changing mechanism, of a multi-cylinder pressure pump inbuilt with said mechanism, a shaft normally operating as a driving shaft for the speed changing mechanism and adapted for intermittent operation as the driving shaft of the pressure pump, operative connections between the cylinders of the pressure pump and said shaft including a spring pressed and pressure controlled two-part friction clutch one part being fast upon said shaft, and operative connections whereby the crankshaft of an engine operates said shaft.

49. The combination with speed changing mechanism, of a multi-cylinder pressure pump inbuilt with said mechanism, a shaft normally operating as a driving shaft for the speed changing mechanism and adapted for intermittent operation as the driving shaft of the pressure pump, operative connections between the cylinders of the pressure pump and said shaft including a spring pressed and pressure controlled two-part friction clutch one part being fast upon said shaft and the other part running loose upon said shaft and being in constant engagement with one of the moving parts of the pressure pump, and operative connections whereby the crankshaft of an engine operates said shaft.

50. The combination with speed changing mechanism, of a multi-cylinder air pressure pump inbuilt with said mechanism, a shaft normally operating as a driving shaft for the speed changing mechanism and adapted for intermittent operation as the driving shaft of the pressure pump, operative connections between the cylinders of the pressure pump and said shaft including a plurality of pistons and connecting rods and a crankshaft geared to a friction clutch member running loose upon said driving shaft, a coöperating friction clutch member fast upon said driving shaft, a spring operated and pressure resisted piston, operative con-

nnections whereby the clutch members are thrown into engagement when the pressure pump is to be operated and automatically thrown out of engagement when the pressure pump operation is to cease, and operative connections whereby the crankshaft of an engine operates said driving shaft.

51. The combination with speed changing mechanism, of an engine crankshaft, operative connections between said mechanism and said crankshaft, and a convertible pressure pump and engine starting device independent of but coöperating with the speed changing mechanism.

52. The combination with speed changing mechanism, of an engine crankshaft, operative connections between said mechanism and said crankshaft, and a convertible pressure pump and engine starting device independent of but coöperating and inbuilt with the speed changing mechanism.

53. The combination with speed changing mechanism, of an engine crankshaft, operative connections between said speed changing mechanism and said crankshaft, a convertible pressure pump and engine starting device independent of but coöperating and inbuilt with the speed changing mechanism, and automatic means for preventing said device from operating as a starting device when it is operating as a pump.

54. The combination with speed changing mechanism, of an engine crankshaft, operating connections between said speed changing mechanism and the engine crankshaft, an air storage tank, a convertible pressure pump and engine starting device coöperating with the tank and independent of but inbuilt with the speed changing mechanism, and valve mechanism whereby said device is prevented from operating as a starting device when it is operating as a pump.

55. The combination with speed changing mechanism, of an engine crankshaft, operating connections between said speed changing mechanism and the engine crankshaft, an air storage tank, a convertible pressure pump and engine starting device coöperating with the tank and independent of but inbuilt with the speed changing mechanism, and valve mechanism whereby said device is prevented from operating as a starting device when it is operating as a pump said mechanism including a series of automatic check valves controlling the flow of air from the device to the tank.

56. The combination with speed changing mechanism, of an engine crankshaft, operating connections between said speed changing mechanism and the engine crankshaft, an air storage tank, a convertible pressure pump and engine starting device coöperating with the tank and inbuilt with the speed changing mechanism, and valve mechanism including a series of automatic check valves

controlling the flow of air from the device to the tank when operating as a pump and also including a spring pressed normally inoperative independent valve whereby said device is prevented from operating as a starting device when it is operating as a pump.

57. In an engine starting device, the combination with an air storage tank, of an engine crankshaft, power transmission mechanism clutched to and operated by said crankshaft, a pressure pump in communication with the tank and automatically operated by said transmission mechanism, means for converting said pump into a motor driven by air from the tank, operative connections whereby the motor causes temporary rotation of the crankshaft, and means for automatically disconnecting the motor and crankshaft when the pressure falls to a predetermined minimum.

58. In an engine starting device, the combination with an air tank, of an engine crankshaft, power transmission mechanism clutched to and operated by the crankshaft, a pressure pump in communication with the tank and automatically operated by the transmission mechanism, valve mechanism for converting the pump into a motor driven by air from the tank, operative connections whereby the motor causes temporary rotation of the crankshaft, and means for automatically disconnecting the motor and crankshaft when the pressure falls to a predetermined minimum.

59. In an engine starting device, the combination with an air tank, of an engine crankshaft, power transmission mechanism clutched to and operated by the crankshaft, a pressure pump in communication with the tank and automatically operated by the transmission mechanism, mechanism including a rotatable and slidale valve for converting the pump into a motor driven by air from the tank, operative connections whereby the motor causes temporary rotation of the crankshaft, and means for automatically disconnecting the motor and crankshaft when the pressure falls to a predetermined minimum.

60. In an engine starting device, the combination with an air tank, of an engine crankshaft, power transmission mechanism clutched to and operated by the crankshaft, a pressure pump in communication with the tank and automatically operated by the transmission mechanism, a series of check valves controlling flow of air from the pump to the tank, mechanism including a rotatable and slidale valve for converting said pump into a motor driven by air from the tank, operative connections whereby the motor causes temporary rotation of the crankshaft, and means for automatically disconnecting the motor and crankshaft when the pressure falls to a predetermined minimum.

61. In an engine starting device, the combination with an air tank, of an engine crankshaft, power transmission mechanism clutched to and operated by the crankshaft, a pressure pump automatically operated by the transmission mechanism, a conduit connecting the pump and tank, means coöperating with the conduit for normally permitting a flow of air through the conduit to the tank only, means for converting the pump into a motor, means coöperating with the conduit whereby air is permitted to flow temporarily from the tank to the motor, operative connections whereby the motor causes temporary rotation of the crankshaft, and means for automatically disconnecting the motor and crankshaft when the pressure falls to a predetermined minimum.

62. In an engine starting device, the combination with an air tank, of an engine crankshaft, power transmission mechanism clutched to and operated by the crankshaft, a pressure pump automatically operated by the transmission mechanism, a conduit connecting the pump and tank, means coöperating with the conduit for normally permitting flow of air through said conduit to the tank only, mechanism for throwing said means out of action to permit air to flow temporarily from the tank, means for converting the pump into a motor operative only when the conduit is open to permit air to flow from the tank, operative connections whereby the motor causes temporary rotation of the crankshaft, and means for automatically disconnecting the motor and crankshaft when the pressure falls to a predetermined minimum.

63. In an engine starting device, the combination with an air tank, of an engine crankshaft, power transmission mechanism clutched to and operated by the crankshaft, a pressure pump automatically operated by the transmission mechanism, a conduit connecting the pump and tank, a check valve coöperating with the conduit for normally permitting flow of air to the tank only, mechanism for throwing and holding the check valve out of action to permit air to flow temporarily from the tank, means for converting the pump into a motor operative only when the check valve is held out of action, operative connections whereby the motor causes temporary rotation of the crankshaft, and means for automatically disconnecting the motor and crankshaft when the pressure falls to a predetermined minimum.

64. In an engine starting device, the combination with an air tank, of an engine crankshaft, power transmission mechanism clutched to and operated by the crankshaft, a pressure pump automatically operated by the transmission mechanism, a conduit connecting the pump and tank, a check valve in

the conduit for normally permitting a flow of air to the tank only, mechanism for throwing and holding the check valve out of action to permit air to flow temporarily from the tank, means for converting the pump into a motor operative only when the check valve is held out of action, and operative connections whereby the motor causes temporary rotation of the crankshaft.

65. In an engine starting device, the combination with an air tank, of an engine crankshaft, power transmission mechanism clutched to and operated by the crankshaft, a convertible pressure pump and motor having a chamber common to both, a conduit connecting the tank and chamber, means cooperating with the conduit for normally permitting flow of air to the tank only, mechanism for throwing and holding said means out of action to permit air to flow temporarily from the tank, and operative connections between the convertible pump and motor and the transmission mechanism whereby the transmission mechanism drives the pump but is driven by the motor and transmits the power of said motor to the engine crankshaft.

66. In an engine starting device, the combination with an air tank, of an engine crankshaft, power transmission mechanism clutched to and operated by the crankshaft, a convertible pressure pump and motor having a chamber common to both, a conduit connecting the tank and chamber, a check valve cooperating with the conduit for normally permitting flow of air to the tank only, mechanism for throwing and holding said check valve out of action to permit air to flow temporarily from the tank, and operative connections between the convertible pump and motor and the transmission mechanism whereby the transmission mechanism drives the pump but is driven by the motor and transmits power of the motor to the engine crankshaft.

67. In an engine starting device, the combination with an air tank, of an engine crankshaft, power transmission mechanism clutched to and operated by the crankshaft, a convertible pressure pump and motor having a chamber common to both, a conduit connecting the tank and chamber, a check valve in the conduit for normally permitting flow of air to the tank only, mechanism for throwing and holding the check valve out of action to permit air to flow temporarily from the tank, and operative connections between the convertible pump and motor and the transmission mechanism whereby the transmission mechanism automatically drives the pump but is driven by the motor and transmits the power of the motor to the crankshaft.

68. In an engine starting device, the combination with an air tank, of an engine

crankshaft, power transmission mechanism clutched to and operated by the crankshaft, a convertible pressure pump and motor having a common chamber, a series of check valves controlling flow of air to the chamber when the device is operating as a pump, valve mechanism controlling flow of air from the chamber when the device is operating as a motor, a check valve within the conduit for normally permitting air to flow to the tank only, mechanism for throwing and holding the conduit check valve out of action to permit air to flow temporarily from the tank to the chamber when the device is operating as a motor, and operative connections between the convertible pump and motor and the transmission mechanism whereby the transmission mechanism automatically drives the pump but is driven by the motor and transmits power of the motor to the crankshaft.

69. In an engine starting device, the combination with an air tank, of an engine crankshaft, power transmission mechanism clutched to and operated by the crankshaft, a convertible pressure pump and motor having a common chamber, a conduit connecting the tank and chamber, a series of check valves controlling flow of air to the chamber when the device is operating as a pump, valve mechanism controlling flow of air from the chamber when the device is operating as a motor, a check valve in the conduit between the chamber and the tank for normally permitting flow of air to the tank only, mechanism for operating the motor valve, connections between said mechanism and the conduit check valve whereby said check valve is thrown and held out of action to permit air to flow temporarily from the tank to the chamber when the device is operating as a motor, and operative connections between the convertible pump and motor and the transmission mechanism whereby the transmission mechanism automatically drives the pump but is driven by the motor and transmits the power of the motor to the crankshaft.

70. In an engine starting device, the combination with an air tank, of an engine crankshaft, power transmission mechanism clutched to and operated by the crankshaft, a convertible pressure pump and motor having a common chamber, a series of check valves in the chamber and controlling flow of air to the chamber when the device is operating as a pump, a valve mechanism controlling outflow of air from the chamber when the device is operating as a motor, a conduit connecting the chamber and tank, a check valve in the conduit for normally permitting flow of air to the tank only, spring pressed normally inoperative mechanism for moving the motor valve to throw it into action, connections between said

- mechanism and the conduit check valve for throwing and holding said check valve out of action while the motor valve is in action, and operative connections between the convertible pump and motor and the transmission mechanism whereby the transmission mechanism automatically drives the pump but is driven by the motor and transmits the power of the motor to the crankshaft.
71. The combination with an engine crankshaft, of a movable power transmission shaft, operative connections between the crankshaft and member, an air storage tank, a motor in communication with the tank, a valve controlling the passage of air from the tank to the motor, and automatically operative means for connecting the motor with the movable member.
72. The combination with an engine crankshaft, of a movable power transmission shaft, operative connections between the crankshaft and power transmission shaft, an air storage tank, a motor in communication with the tank, a valve controlling the passage of air from the tank to the motor, and pressure operated means for automatically connecting the motor with the power transmission shaft.
73. The combination with an engine crankshaft, of a movable power transmission shaft, operative connections between the crankshaft and power transmission shaft, an air storage tank, a motor in communication with the tank, a valve controlling the passage of air from the tank to the motor, and pressure operated means controlled by the valve for automatically connecting the motor with the power transmission shaft.
74. The combination with an engine crankshaft, of a movable power transmission shaft, operative connections between the crankshaft and power transmission shaft, an air storage tank, a motor in communication with the tank, a valve controlling the passage of air from the tank to the motor, and pressure operated means controlled by the valve and including a cylinder and a piston within the cylinder and operative connections for automatically connecting the motor with the power transmission shaft.
75. The combination with an engine crankshaft, of a movable power transmission shaft, operative connections between the crankshaft and power transmission shaft, an air storage tank, a motor in communication with the tank, a valve controlling the passage of air from the tank to the motor, automatically operative means for connecting the motor with the power transmission shaft, and a housing into which the motor exhausts and which serves as a muffler for the exhaust.
76. In an engine starting device, the combination with an air tank, of a plurality of cylinders in communication with the tank,
- a plurality of pistons within the cylinders, operative connections whereby said pistons may be driven to cause them to operate to compress air within the tank, means for causing said pistons and cylinders and connections to operate as a motor driven by air from the tank, and operative connections whereby said pistons cause temporary rotation of an engine crankshaft, said connections including a power transmission shaft normally acting to transmit the power of the engine to a point beyond the starting device.
77. The combination with an internal combustion engine, of a clutch mechanism coöperative with the engine and adapted to absorb shock due to clutch engagement with the engine under excessive load, an air storage tank, a pressure pump in communication with the tank, automatically operative connections coöperating with the pump whereby said pump is caused to normally maintain a predetermined pressure within the tank, and operative connections between the tank and engine whereby pressure from the tank is caused to start the engine through the agency of the clutch mechanism.
78. The combination with speed changing mechanism, of a pressure pump independent of the speed changing mechanism, operative connections for said pump, and a housing inclosing said mechanism and said pump and said connections whereby said mechanism and said pump are lubricated from a common source.
79. The combination with speed changing mechanism, of an engine starting device independent of the speed changing mechanism, operative connections for said device, and a housing inclosing said mechanism and said device and said connections whereby said mechanism and said device are lubricated from a common source.
80. The combination with speed changing mechanism, of a convertible pressure pump and engine starting device independent of the speed changing mechanism, operative connections for said pump and device, and a housing inclosing said mechanism and said pump and said device and said connections whereby said mechanism and said pump and said device are lubricated from a common source.
81. The combination with speed changing mechanism, of a convertible pressure pump, and engine starting device, operative connections for said pump and device, and a sectional housing for said mechanism and said pump and said device and said connections whereby said mechanism and said pump and said connections and said device are lubricated from a common source, one of the sections of the housing supporting the speed changing mechanism and another section of the housing supporting the pump and starting device.

82. The combination with speed changing mechanism, of a convertible pressure pump and engine starting device, operative connections for said pump and device, and a superposed three-section housing inclosing said mechanism and said pump and said device, and said connections whereby said mechanism and said pump and said device are lubricated from a common source, the lower section supporting the speed changing mechanism and the upper section supporting the convertible pump and starting device and the middle section operating as a spacer between the upper and lower sections.
83. The combination with an engine crankshaft, of a convertible pressure pump and engine starting device, and operative connections between said crankshaft and said convertible pump and said engine starting device including a clutch mechanism which controls the power transmission devices driven by the engine crankshaft.
84. In an engine starting device, the combination with an air storage tank, of an engine crankshaft, operative connections including a power transmission clutch between the tank and crankshaft whereby air from the tank is caused to operate the crankshaft, and whereby the power of the engine when running is transmitted, a check valve controlling flow of air to and from the tank and normally operative to prevent egress of air from the tank, and operative connections whereby the check valve is thrown out of normal action only when the crankshaft is to be operated through the agency of the power transmission clutch.
85. The combination with an engine starting device, of an engine controlling device movable in and out of operative position, operative connections whereby the starting device is inoperative except when the controlling device is in operative position, speed changing mechanism, and means cooperating with said mechanism and said starting device whereby the starting device is held in inoperative position except when the speed changing mechanism is in neutral position.
86. The combination with an engine starting device, of an engine controlling device movable in and out of operative position, interlocking connections between said devices whereby operation of the starting device moves the controlling device into operative position, speed changing mechanism, and means cooperating with said mechanism and said starting device whereby said starting device is held in inoperative position except when the speed changing mechanism is in neutral position.
87. The combination with an engine starting device, of an engine controlling device movable in and out of operative position, operative connections whereby the starting device is inoperative except when the controlling device is in operative position, speed changing mechanism inbuilt with the starting device, and means coöperative with said mechanism and said starting device whereby said starting device is held in inoperative position except when the speed changing mechanism is in neutral position.
88. The combination with an engine starting device, of an engine controlling device movable in and out of operative position, interlocking connections between said devices whereby operation of the starting device moves the controlling device into operative position, speed changing mechanism inbuilt with the starting device, and means coöperating with said mechanism and said starting device whereby said starting device is held in inoperative position except when the speed changing mechanism is in inoperative position.
89. The combination with an engine starting device comprising a convertible pressure pump and air motor and operating connections, of an engine controlling device movable in and out of operative position, and operative connections whereby the starting device is inoperative as a motor except when the controlling device is in operative position.
90. The combination with an engine starting device comprising a convertible pressure pump and air motor and operating connections, of an engine controlling device movable in and out of operative position, and interlocking connections between said devices whereby operation of the starting device as a motor moves the controlling device into operative position.
91. The combination with a speed changing mechanism, of a power operated engine starting mechanism, and operative connections common to both mechanisms whereby either of said mechanisms may be selectively operated but neither mechanism can be operated while the other is in operation.
- In testimony whereof, I have signed my name to this specification in the presence of two subscribing witnesses.
- SYDNEY I. PRESCOTT.
- Witnesses:
- FRANK H. VICK, Jr.,
ELIZABETH LOUISE RUSSELL.
